UNITED STATES PATENT OFFICE.

HENRY E. RAYMOND, OF SCHENECTADY, NEW YORK, ASSIGNOR TO THE GENERAL ELECTRIC COMPANY, A CORPORATION OF NEW YORK.

LIGHTNING-ARRESTER.

SPECIFICATION forming part of Letters Patent No. 727,688, dated May 12, 1903.

Application filed July 22, 1899. Serial No. 724,772. (No model.)

To all whom it may concern:

Be it known that I, HENRY E. RAYMOND, a citizen of the United States, residing at Schenectady, county of Schenectady, State of New York, have invented certain new and useful Improvements in Lightning-Arresters, (Case No. 1,342,) of which the following is a specification.

This invention relates to improvements in lightning-arresters; and the function of devices constructed in accordance therewith is to provide a path of increased facility for the lightning charge, with means for effectually preventing the following through of the line-current to continue the arc.

The invention consists of various elements, the offices and character of which are described herein and particularly pointed out in the claims.

The difficulty with previously-existing lightning-arresters has been to obtain a mean between those having a striking distance too great for the lightning and those having air-gaps permitting the continuation of wasteful and destructive arcs by the line-currents. The object of the arresters constructed in accordance with this invention is to provide means for furnishing an easier path for the lightning charge, whereby the air-gaps may be increased to such an extent that arcs cannot be maintained across them by the line-current.

I have found that the capacity of dischargers is increased by reducing the mass, and hence the capacity of dischargers which are made hollow is greater than that of solid dischargers. The action of a discharger of large mass in conducting heat away from the air-gap surfaces is lost to a large extent in this case; but this heat will be carried off by radiation from the exterior surfaces and be conducted through the thin wall to the inner surfaces of the hollow body and the radiation greatly facilitated by exposing these inner surfaces. I have found also that if auxiliary members, consisting of pieces of metal or hard rubber or of other substances, be held in proximity to air-gaps between metallic dischargers the resonant or capacity effect appears to be increased, the arresters discharge more freely, and the air-gaps may be widened to

the extent of effectually preventing the line-current from continuing an arc over the gap without danger of the lightning charge breaking down the line-insulation. In practice to 55 obtain this result I have mounted pieces of brass upon the tops of the dischargers, the pieces extending over the nearest air gap or gaps. The discharge in this case does not differ in location from that commonly occurring in the ordinary arrester provided with metallic dischargers—that is, the pieces themselves do not carry the charge, but increase the tendency of the latter to jump across the air-gap from one discharger to the next without in any manner affecting the action of the line-current, which has relatively low frequency. The above result is also effectively accomplished by the auxiliary members when the dischargers have non-metallic centers, as 70 in the case of large-capacity hollow dischargers; but these auxiliary members may be attached to the ordinary solid discharger.

Of the drawings, Figure 1 is a plan of a single arrester embodying my invention. Fig. 2 is a side elevation of the same. Fig. 3 is a plan of a double arrester, also embodying my invention, each side of the line being adapted to discharge to ground through the terminal T'; and Fig. 4 is a sectional view of one of 80 the dischargers.

A suitably-insulated plate A, as of slate, forms the base upon which the terminals T and T' and the dischargers D are mounted. The terminals T are adapted to be connected 85 with the line and T' with the ground.

Mounted upon the dischargers D by any suitable means, as by the screws S, are the auxiliary members or "teasers" X, in such position that they bridge over the adjacent 90 air-gaps.

The dischargers D are or may be hollow, with non-metallic centers or posts P, having a screw-threaded end of smaller diameter by which they are secured to the base A and 95 their lower edges held above the base, as shown at O, in order to permit a free circulation of air.

I prefer to insert non-inductive resistances R in series with the air-gaps for the purpose 100 of blocking the line-current, and these resistances, which are best formed of short carbon

rods, are supported in clips or brackets C. This is the standard form of arrester and operates most effectively; but the invention is not limited to the applications herein disclosed, but may be adapted to various types of arresters.

What I claim as new, and desire to secure by Letters Patent of the United States, is—

1. In a lightning-arrester, the combination 10 with cup-shaped dischargers arranged in proximity to each other to include air-gaps between them, a base, posts secured in said base, and means for securing the closed ends of the dischargers to the tops of the posts, so that 15 the lower edges of the dischargers are held above the base to permit a free circulation of air.

2. In a lightning-arrester, the combination 20 of metallic dischargers separated from each other by an air-gap, and a metallic strip or projection of metal carried by one discharger and extending toward but not into contact with an adjacent discharger for facilitating a discharge of lightning across said air-gap.

25 3. In a lightning-arrester, the combination of dischargers separated by an air-gap, and a conducting strip or member electrically con-

nected to one of said dischargers and extending toward an adjacent discharger but separated from the latter by a distance not less than the length of said air-gap.

4. In a lightning-arrester, the combination 30 of dischargers separated by air-gaps, of auxiliary members arranged in proximity to said dischargers for increasing the tendency of lightning to discharge across said air-gaps but arranged so that the paths between said dischargers through said members include a total length of air-gap not less than that between said dischargers.

5. In a lightning-arrester, the combination 35 of hollow metallic dischargers arranged side by side and separated by an air-gap, and an auxiliary member consisting of a piece of metal mounted on and electrically connected 40 to one discharger and extending into the vicinity of an adjacent discharger.

In witness whereof I have hereunto set my hand this 20th day of July, 1899.

HENRY E. RAYMOND.
